ABSTRACT OF THE DISCLOSURE

A manual indexing mechanism for a dial feed mechanism which is operative to disconnect the dial feed from the press drive. The mechanism includes timing means which assure the proper timed relationship when the dial feed is re-connected to the press drive.

This invention relates to dial feeds for a press and, more particularly, to a manual indexing mechanism to permit manual indexing of the dial feed.

Most dial type feed devices comprise a rotatable disc or "dial" provided with a plurality of work receiving openings. The workpieces to be formed are deposited into the openings and the dial is rotated to a position where one of the workpieces is delivered to the die. The ram of the press is then reciprocated through the dial opening and into the die thus forming the previously deposited workpiece. Subsequently, the ram is withdrawn and means actuated to eject or lift the formed workpiece from the die back up to the same opening in the dial. Rotation of the dial then removes the formed workpiece from between the ram and die and delivers it to a position where it can be removed from the dial. Simultaneously, another opening in the dial delivers a new workpiece to the die.

It is readily apparent that the movement of the dial must be properly co-ordinated with the movement of the ram. Accordingly, the drive mechanism for the dial feed usually is connected through appropriate means to the drive mechanism for the ram so that as the ram is reciprocated, the proper co-ordination of the dial is achieved.

It sometimes occurs in the use of such a dial feed mechanism, that there is a need for rotating the dial feed independent of the ram. One such instance when this may occur is when there is a broken part in the die which then requires the indexing of the dial feed mechanism to facilitate removal and replacement of the broken die. In such circumstances, it is desirable only to rotate the dial feed mechanism rather than cycle the entire press mechanism.

It is the primary object of this invention to provide a manual release and indexing mechanism for the dial feed drive shaft whereby the feed drive shaft may be rotated independently of the press drive shaft.

In accordance with the broad aspect of this invention, it is contemplated that a press of the type having a rotating press drive shaft, a dial feed mechanism and a feed drive shaft will employ means interconnecting the press drive shaft with the feed drive shaft for synchronous rotation with the interconnecting means including means for manually disengaging the feed drive shaft from the press drive shaft whereby the feed drive shaft may be rotated independently of the press drive shaft. The invention further contemplates means whereby the synchronism of the two drive shafts may be re-established when the feed drive shaft is reconnected with the press drive shaft.

More specifically, the invention contemplates a disengageable drive means between the press drive shaft

2

and the feed drive shaft which disengageable means includes a first drive member in the form of a gear rotatably supported on the feed drive shaft with the gear driveably connected to the press drive shaft. A second gear is secured to the feed drive shaft for rotation therewith but may move longitudinally of the feed drive shaft into and out of meshing engagement with the first gear. Spring means normally bias the second gear into meshing engagement with the first gear. A latch detent on the second gear is operative to lock the second gear in a disengaged position when so desired whereby the feed drive shaft is disconnected from the press drive shaft and may be manually rotated to index the dial feed mechanism. A tooth on one of the gears is removed and a valley between two teeth on the other gear is filled in so that the two gears will mesh only in one position thereby assuring the proper timed relationship between the press drive shaft and feed drive shaft whenever the two gears are intermeshed.

Other features of the invention will become more apparent upon a complete reading of the following description which, together with the attached drawings, discloses but a preferred embodiment of the invention. Such preferred embodiment is not intended to limit since it constitutes but one way in which the principles of the invention may be employed.

Referring now to the drawings wherein like reference numerals indicate like parts in the various views.

FIGURE 1 is a partial sectional view through the feed drive shaft mechanism of a press.

FIGURE 2 is a sectional view taken along line 2—2 of FIGURE 1.

Referring now to FIGURE 1, there is illustrated the mechanism comprising the instant invention. It is to be understood that the elements illustrated are incorporated in a conventional power press, the details of which form no portion of this invention and are well known to those skilled in the press art. Thus, the press would comprise a standard press frame 10 with a press drive shaft supported for rotation in the crown of the press. A dial feed mechanism 12 would be supported in the bed of the press with the dial feed actuating mechanism connected by a coupling 14 to a dial feed shaft 16 rotatably supported by a bushing 18 in the press. The shaft 16 is connected by appropriate means for synchronized rotation with the press drive shaft and it is this interconnection with the press drive shaft which is the subject of this invention.

As shown in FIGURE 1, there is a timing belt sheave 20 rotatably supported on the flanged bushing 18. A timing belt 22 passes around the sheave 20 and, through appropriate sheaves on the press drive shaft, interconnects the sheave 20 for rotation with the press drive shaft.

The sheave 20 is recessed in one axial face thereof and has secured in the recess a ring gear 24 with the gear having internal teeth which face toward the shaft 16. A hub 30 is received over the end of the shaft 16 projecting through the sheave 20 and includes external teeth 32 which form a gear on the periphery thereof with the external teeth being adapted to engage the teeth on the ring gear 24. A key 34 connects the hub 30 with the shaft 16 for unitary rotation therewith; however, the keyed connection between the hub and the shaft 16 permits the hub 30 to move longitudinally of the shaft 16. A nut 36 is threaded on the other end of the shaft 16 with a spring 38 encircling the shaft and being interposed between the nut 36 and the hub 30 thereby exerting a biasing force on the hub 30 to move the hub toward the sheave 20. The hub 30 further includes a radially extending rib 40 which facilitates manually grasping the hub 30 and moving it longitudinally of the shaft against the bias of the spring 38.

A detent mechanism is employed to retain the teeth 32

on hub 30 disengaged from the gear 24 on sheave 20. The 5 detent mechanism comprises a bore 42 formed in the hub 30 with a plunger or locking pin 44 passing through a cap nut 46 into the bore 42. The pin has a head 48 at one end and a spring 50 tending to bias the locking pin radially inward into engagement with the periphery of the shaft 16. A circumferential groove 52 is formed in the shaft with the position of the groove 52 being longitudinally displaced from the normal position of the lock pin when the hub 30 is biased into engagement with the ring gear 24. It will be appreciated that should the hub 30 be withdrawn longitudinally along the shaft 16 away from the sheave 20, the spring 50 will act on the lock pin 44 to bias the lock pin into the groove 52 as the pin is positioned thereover. In this condition, the hub 30 will be locked against longitudinal movement along the shaft 16 and thereby be retained in a disengaged position.

The above-described mechanism provides a means whereby the dial feed mechanism may be manually rotated independent of the press drive system. Thus, in the condition of the parts as shown in FIGURE 1, rotation of the press drive will, through the belt 22, drive the sheave 20 which through the meshing engagement of the gear 24 with the teeth 32 on the hub 30 will drive the hub 30 and thereby the shaft 16. However, if it is desired to disconnect the dial feed mechanism from the press drive, all that is necessary is to grasp the hub 30 and pull the hub longitudinally along the shaft 16 against the bias of the spring 38 until the locking pin 44 is positioned over the groove 52. In this position, the locking pin will snap into the groove due to the action of the spring 50 and lock the hub in a disengaged position thereby isolating the driving sheave 20 from driving relationship with the shaft 16. With the hub 30 disengaged, the shaft 16 may be rotated manually by applying a wrench to the nut 36 and rotating the shaft and thereby the dial feed mechanism. To re-engage the shaft 16 with the press drive system, all that is required is to lift the locking pin 44 and the spring pressure exerted by the spring 38 will move the hub 30 longitudinally of the shaft 16 into engagement with the ring gear 24. To limit the movement of the hub 30 under the bias of the spring 38, there is provided a stepped shoulder 16a on shaft 16 which functions as a stop to position the hub and its associated gear with the ring gear 24.

It is, of course, necessary to maintain the proper timed relationship between the press drive and the dial feed mechanisms. Accordingly, to permit the manual rotation of the feed mechanism while yet assuring the proper timed relationship when the gears are re-engaged, there is provided timing means which assure that the gears will re-engage only in the proper timed relationship. Thus, referring to FIGURE 2, the ring gear 24 is of a conventional spur gear design with the exception that the valley between two adjacent teeth is filled in to form a timing lug 54. Similarly, one of the teeth 32 on the hub 30 is removed to accommodate the timing lug 54. With this arrangement, the two gears can mesh only in one position thereby assuring that the timing between the press drive shaft and the feed shaft is at all times maintained.

Modifications and changes in the described invention will suggest themselves to those having ordinary skill in the art. Changes and modifications such as these are contemplated by the principles of this invention so that, although for ease of description the principles of the invention have been set forth in connection with but one illustrated embodiment, it is not intended that this embodiment or the terminology employed in describing it is

to be limiting, but rather it is my desire to be restricted only by the scope of the appended claims.

Having thus described my invention, I claim:

1. In a press of the type having a rotating press drive shaft, a dial feed mechanism, a feed drive shaft and means interconnecting said feed drive shaft with said press drive shaft, the improvement comprising:

said interconnecting means including manual means for connecting and disconnecting said feed drive shaft from said press drive shaft whereby said feed drive shaft may be manually rotated independently of said press drive shaft.

2. The improvement of claim 1 wherein said interconnecting means further includes timing means operative to prevent the interconnection of said feed drive shaft with said press drive shaft other than in a predetermined time relationship.

3. The improvement of claim 1 wherein said interconnecting means includes a first drive member rotatably supported on said feed drive shaft and drivably connected to said press drive shaft,

a second drive member in driving engagement with said feed drive shaft; and,

means for selectively interconnecting said first and second drive members in driving relationship whereby said feed drive shaft may be driven by said press drive shaft.

4. The improvement of claim 3 wherein said first drive member comprises a first gear and said second drive member comprises a second gear,

said second gear being secured to said feed drive shaft for unitary rotation therewith and movement longitudinally thereof.

5. The improvement of claim 4 wherein said selective interconnecting means comprises means normally biasing said second gear into meshing engagement with said first gear.

6. The improvement of claim 5 and further including detent means for maintaining said second gear out of meshing engagement with said first gear.

7. The improvement of claim 6 and further including means on said feed drive shaft for manually rotating said feed drive shaft.

8. The improvement of claim 6 wherein said gears include means preventing meshing interengagement other than in a predetermined relationship.

9. The improvement of claim 3 wherein said drive members include means for preventing the driving engagement of said members other than in a predetermined timed relationship.

10. The improvement of claim 6 wherein said detent means includes a groove in said feed drive shaft and a locking pin on said second gear.
